ANNIE CONLEY, OF EAU CLAIRE, WISCONSIN

LIQUID COOLER

Application filed January 23, 1929. Serial No. 234,419.

My invention relates to improvements in coolers.

The object of my invention is to provide a cooler for fluids wherein a constant change of coolant may be maintained without danger of overflow which will dilute the material to be cooled.

More particularly stated, it is the object of my invention to provide a cooler of the floating tray type, wherein the liquid, after passing in a thin stream over the cooling surface of a floating tray, may be discharged automatically from the tray by means of a drain, the structure of the cooler pan and its outlet being such that overflowing coolant is positively diverted from the stream of fluid to be cooled.

In the drawings:

Figure 1 is an isometric view of my device with a portion of the pan and tray broken away to show the essential features of my invention.

Figure 2 is a vertical section through a portion of my complete device.

Like parts are identified by the same reference characters throughout the several views.

The cooler including my invention is composed of two major elements,—a pan 10 and a tray 11, the pan being formed in any acceptable shape to provide a space 12 for coolant, which in the dairy industry will usually be cold water. At spaced points around the periphery of the pan 10, and at a convenient height I provide supports 13 to receive the tray 11 and support it when the device is not in operation, or, in other words, when the coolant is not present in the pan.

In the usual operation of my device cooling water or other coolant may be introduced to the pan through a spout 14, and this coolant will usually be introduced in the form of a steady stream to maintain a constant temperature in the coolant in the pan. It is therefore necessary to draw off a similar amount of coolant through some drain, which will prevent an overflow of coolant from the pan into the tray 11. It is the overflow device and provision for the drainage of the tray 11 which comprises the essence of my invention, and it is the problem of drainage

of the floating tray in conjunction with the disposal of excess coolant, which comprises the problem that it is the purpose of my invention to meet.

Obviously it is in the dairy industry and in other industries where cooling processes for fluids are necessary and where dilution of the fluids to be cooled must be studiously avoided that my invention is of value.

In my device I have provided a series of baffles 15, which extend partially or substantially across the width of my tray alternately, first from one side and then from the other, to form a tortuous path for the passage of a trickle or fine stream of fluid to be cooled to the end that the fluid will pass over an extended length of cooled surface before reaching a drain 16 at the other end of the tray. The drain 16 may comprise a short nipple extending downwardly from the bottom of the tray, as shown at 17. The drainage of fluid from the nipple 17 must be protected completely from the flow of coolant in and through the pan 10, and means flexible and yet positive for the disposition of the cooled fluid from the tray comprise the elements making up my invention.

I have set off a portion 18 of the bottom of the pan 10 and have walled this off with an annular rim or wall 19, so as to set off a chamber or a receptacle wherein coolant from the pan may overflow, and a pan drain 20 is provided to carry off overflow coolant and dispose of it in any manner desired.

Extending from a point without the pan through the floor of the pan into the chamber surrounded by the wall 19, I have provided a conduit 21, which may extend upwardly in this chamber sufficiently to reach the nipple 17 when the tray is positioned in the pan and supported either by the coolant in the pan as a floating object or supported by the angular supports 13 heretofore referred to. It will be obvious from the description of the operation of my device as hereinafter set forth, that the conduit 21 may be introduced through a wall of pan and through the rim 19 to accomplish the same result, but I prefer to extend the conduit through the floor or bottom of the pan

so that only one fluid tight connection need be provided between the conduit and such portions of the pan as are required to hold coolant.

5 In operation my device is adapted to receive fluid at the one end of the tray, and by reason of the baffles this fluid will be conducted back and forth across the pan to a point where it is discharged through the drain 16 and nipple 17 into the conduit 21. From this conduit it may be passed to any desired container. Throughout the passage of the fluid across the bottom of the tray in the manner indicated, the effect of coolant 10 upon the bottom of the tray is secured by means of any fluid or liquid coolant introduced into the pan through the spout 14 and the pan will float upon the coolant to a height governed by the height of the coolant as it 15 overflows the rim of the wall 19, and is discharged through the drain pipe 20.

The advantage of my device will be seen from this explanation, for no matter how rapidly the coolant is supplied through the 20 spout 14, the unrestricted overflow over the wall 19 can never reach the open joint between the nipple 17 and the conduit 21, and dilution of the cooled fluid is impossible.

I claim:

30 1. A pan for coolant provided with an annular rim upstanding from its bottom, a conduit extending from without the pan to a point within the enclosure of the rim, a drain for the portion of the pan enclosed by the 35 rim, and a tray to float on the coolant in the pan and provided with a drain comprising a nipple receivable in the conduit.

2. A cooler including a pan for coolant provided with an overflow compartment, a 40 drain for said compartment, an upstanding conduit in said compartment opening into a space outside the pan, and a tray adapted to float on the coolant in the pan and provided with a drain pipe loosely receivable into the conduit.

45 3. A cooler comprising a pan for liquid coolant, a tray provided with baffles extended upwardly at spaced points along the bottom of the pan and describing a tortuous path for liquid to be cooled, a nipple comprising a drain for the tray, a partition for setting off a portion of the pan from the coolant therein, a drain for said portion of the pan, and a conduit extending from without the pan to a 50 point adjacent the top of the partition and within its confines to receive the nipple of the tray and conduct fluid therefrom undiluted by coolant.

60 4. A cooler including a pan, an overflow compartment for the pan provided with a drain, a tray adapted to float upon coolant in the pan, a conduit extending from without the pan through the overflow compartment, and an outlet for the tray for delivering the 65 contents of the tray into the conduit, said

conduit and said outlet being spaced from the path of coolant overflowing into the outlet compartment.

5. A cooler including a pan, an overflow compartment for the pan provided with a drain, a tray adapted to float upon coolant in the pan, a conduit extending from without the pan through the overflow compartment, an outlet for the tray for delivering the contents of the tray into the conduit, said conduit and said outlet being spaced from the path of coolant overflowing into the outlet compartment, a spout for directing coolant into the pan along a path separated from the tray, and supports to maintain the tray in a level position when the pan is emptied of coolant. 70 75 80

6. A pan for coolant provided with an annular rim upstanding from its bottom, a conduit extending from without the pan to a point within the enclosure of the rim and spaced from the wall thereof, and a tray adapted to float upon coolant in the pan and provided with a nipple receivable in the conduit to discharge the contents of the tray into 90 the conduit. 95

7. A cooler including a pan for coolant provided with an overflow compartment and spaced supports substantially level with the top margin of the overflow compartment, a drain for said compartment, an upstanding conduit in said compartment opening into a space outside the pan, and a tray upon said supports adapted to float on the coolant in the pan when the depth of coolant attains a 100 height greater than the supports, said tray being provided with a drain pipe loosely receivable into the conduit. 100
